United States Patent

Des. 239,467

Patented Apr. 6, 1976

239,467

PICTURE VIEWER

Alfons Adriaan den Ouden, Antwerp, Belgium, assignor
to Brabo Corporation Naamloze Vennootschap, Ant-
werp, Belgium

Filed Aug. 9, 1974, Ser. No. 496,352

Claims priority, application Great Britain Feb. 15, 1974

Term of patent 14 years

Int. Cl. D16—03

U.S. Cl. D61—1 N

Fig. 1

Fig. 2

Fig. 3

Fig. 4

FIG. 1 is a developed outside plan view showing my new design;

FIG. 2 is an inverted developed plan view thereof;

FIG. 3 is a side view thereof; and

FIG. 4 is a perspective view thereof showing the viewing device folded into position for use.

The diagonally shaded portions of FIGS. 1, 2 and 4 represent a mirrored surface.

I claim:

The ornamental design for a picture viewer, as shown and described.
